UNITED STATES PATENT OFFICE.

EDWARD S. CLARKE, OF RICHMOND, VIRGINIA; VIRGINIA TRUST COMPANY, EXECUTOR OF SAID CLARKE, DECEASED, ASSIGNOR OF ONE-HALF TO ISAAC J. MARCUSE, OF RICHMOND, VIRGINIA.

DOUBLE-CUT TOOL.

1,135,157.

Specification of Letters Patent. Patented Apr. 13, 1915.

Application filed June 3, 1914. Serial No. 842,564.

To all whom it may concern:

Be it known that I, EDWARD S. CLARKE, a citizen of the United States, residing in Richmond, in the county of Henrico and State of Virginia, have invented a new and useful Improvement in Double-Cut Tools, of which the following is a specification.

My invention relates to double cut tools designed and intended for use in shapers, 10 planers and the like where the tool head and bed carrying the work have a relative planular reciprocating movement.

One of the principal objects of the invention is the provision of a tool for a planer 15 or shaper which will cut with equal efficiency and accuracy on both the forward and return strokes of the tool head or bed carrying the work.

A further object of the invention is the 20 provision of easily operable means in a tool of this character for adjusting a cutting element or member, provided accurately by the use of simple devices and mechanisms, so that such cutting element, and any associated cutting element, will produce a 25 smooth, even surface on the work being operated upon.

Other objects and advantages of the invention will be apparent as it is understood 30 from the following description when considered in connection with the accompanying drawing illustrating a preferred embodiment thereof.

On the drawing, Figure 1 is a front elevation of a planer provided with a tool embodying my invention; Fig. 2 is an enlarged vertical sectional view of the tool embodying my invention taken substantially on the line 2—2 of Fig. 1; Fig. 3 is a similar view taken 35 at right angles to the view shown in Fig. 2 and substantially on the line 3—3 thereof; Fig. 4 is a horizontal sectional view taken substantially on the line 4—4 of Fig. 2; Fig. 5 is a vertical sectional view taken substantially on the line 5—5 of Fig. 3; and Fig. 6 is an end elevation of the means for affecting 45 the vertical adjustment of the tool.

For the purpose of illustrating my invention I have shown it embodied in a tool 11 50 mounted in a planer 12 of any well known or preferred type. In the present instance this tool consists of a head 13 from which extends a shank 14 adapted to be secured in the ram of the shaper or in the head of the

planer. Two tool receiving apertures 15 extend through the head and in each of them is mounted a tool holder 16, 17. These apertures extend completely through the head and are provided with inclined surfaces 18 against which the lower end of the tool holders 16 may rest while the tool is cutting to hold the tool rigidly to the work. One of the tool holders 16 is adjustable with respect to the other, both vertically and transversely, so that the two cutting elements or tools 19, 20, which are positioned in the holders 16, 17, may be readily brought into accurate relation each with the other. The mounting of the holder which permits these adjustments to occur is best shown in Figs. 2 and 3, from which it will be noted that a pair of aligned apertures 21 and 22 extend from the recess 15 through the sides of the head, and about these apertures are formed shoulders 23 and 24 which, with the side walls of the head, form bearings for a pivot shaft generally designated at 27 for the tool holder 16. The transverse adjustment is effected by a collar 26 in threaded engagement with the shoulder 23 at the left in Fig. 3. This collar is engaged with one end of the shaft 27 by means of a half-collar 28 fastened on the end of the sleeve and taking into a groove 29 in a bushing or sleeve 30, secured on the end of the shaft 27. Rotation of the sleeve 26 will move the shaft 27 longitudinally and across the head, carrying with it the holder 16. The holder 16, in the present instance, is held against movement along the shaft by an enlarged portion 31 of the shaft 90 at one side and by a lock-nut 32 at the other, so that as the shaft is moved across the head the holder 16 will move with it.

The vertical adjustment of the holder 16 and the tool 19 carried thereby is effected 95 by an eccentric 33 formed on the shaft 27 within the holder so that if the shaft 27 is rotated the holder will be raised or lowered by the eccentric 33. A rotary movement is given the shaft 27 by a sleeve 34 threaded on the shoulder 24 (at the right in Fig. 3), which sleeve is provided with a stud 35 extending into a key-way or slot 36 in the enlarged end 31 of the shaft. This key-way permits the transverse adjustment without 100 disturbing the position of the stud 35 and the half-collar 28 connecting the sleeve 26 with the left-hand end of the shaft 27 per-

mits vertical adjustment of the holder without disturbing the position of the transverse adjustment. Lock-nuts 37 and 38 threaded upon the sleeves 23 and 24 provide means 5 for locking the sleeves 26 and 34 in adjusted position. In the present instance the other tool holder 17 is pivotally mounted in the head upon a fixed pivot or shaft 39, although it may be mounted similarly to the holder 16 10 if desired.

When the parts are to be assembled the shaft 27 is inserted through the aperture 22, which is the larger aperture or the aperture adapted to receive the enlarged portion 15 31 of the shaft, the holder 16 and lock-nut 32 being threaded over the small end of the shaft as it is inserted in the head, the shaft being moved endwise into position and the holder being engaged on the eccentric where it is secured by turning the lock-nut 32 against it. The sleeves 26 and 34 may then be slipped into place and secured respectively by the half-collar 38 and the stud 35. In use the tools 19, 20 are first 20 positioned in their respective holders and the holder 16 with its tool is then adjusted for height and positioned by manipulating the sleeve 34, and is then adjusted transversely in accordance with the width of cut 25 made by each tool in its cutting stroke. It will be apparent that these adjustments may be varied in order and that they can be readily made by any person sufficiently skilled to manipulate a planer or shaper of 30 any of the well known types. The lock-nuts 37 and 38 maintain the parts in the desired 35 adjusted relations throughout the operation of the planer.

It is believed that the invention and many 40 of its attendant advantages will be understood from the foregoing without further description, and it will be obvious that various changes may be made in the form, construction and arrangement of the parts 45 without departing from the spirit and scope of the invention within the scope of the appended claims or sacrificing any of its material advantages, the form hereinbefore described being merely a preferred embodiment 50 thereof.

I claim:

1. A double cut shaper or planer tool comprising, in combination: a tool head; a tool holder mounted therein and adapted to 55 hold a cutting tool; a shaft mounted in the said head; means for adjusting the said shaft longitudinally and means for adjusting it around its axis, said two adjusting means being independent of each other so 60 that each permits the operation of the other: an eccentric fixed on the shaft; and a second tool holder adapted to hold a cutting tool and mounted on the said eccentric; whereby the second tool may be adjusted relative to 65 the first tool.

2. A shaper or planer tool comprising a head, a pivot shaft mounted in the head and having an eccentric, a tool holder mounted on the said eccentric and held from movement longitudinally of the shaft, means connecting the said head with the shaft for adjusting the shaft longitudinally without interfering with the turning of the shaft, and means connecting the said head with the shaft for adjusting the shaft and eccentric 75 around their axis without interfering with the longitudinal movement of the shaft.

3. A shaper or planer tool comprising a head, a pivot shaft mounted in the head and having an eccentric, a tool holder mounted 80 on the said eccentric and held from movement longitudinally of the shaft, means connecting the said head with the shaft for adjusting the shaft longitudinally without interfering with the turning of the shaft, and 85 means connecting the said head with the shaft for adjusting the shaft and eccentric around their axis without interfering with the longitudinal movement of the shaft, combined with another tool holder mounted 90 in the said head and relative to which the first tool holder is adjusted by the said movements of the shaft.

4. A shaper or planer tool comprising a head having aligned externally screw-threaded tubular bearing shoulders extending outwardly from opposite sides of the head, a pivot shaft mounted in the bearings formed by the said shoulders and having an eccentric, a tool holder mounted on the said eccentric and held thereon from movement longitudinally of the shaft, means connecting one of the said shoulders with one end of the shaft for adjusting the shaft longitudinally without interfering with the turning of the shaft, and means connecting the other of the said shoulders with the other end of the shaft for adjusting the shaft around its axis without interfering with the longitudinal movement of the shaft. 105

5. A shaper or planer tool comprising a tool head, a longitudinally movable pivot shaft secured thereto, a cutting element, a holder for said cutting element pivotally mounted on said pivot shaft and held 115 against movement longitudinally thereof, and means for moving said pivot shaft longitudinally to adjust the position of said element in the head, combined with another cutting element relative to which the said 120 shaft and its suspended cutting element is adjusted.

6. A shaper or planer tool comprising a head having an outwardly extending externally threaded bearing shoulder, a pivot shaft disposed through said bearing shoulder, a cutting element, a holder for said cutting element pivotally mounted on said pivot shaft and held against movement longitudinally thereof, and a sleeve rotatably connected to 130

said pivot shaft and engaging the external threads on said shoulder for moving said pivot shaft longitudinally to adjust said element in said head, combined with another 5 cutting element relative to which the said shaft and its suspended cutting element is adjusted.

7. A shaper or planer tool comprising a head having an outwardly extending externally threaded bearing shoulder, a pivot shaft disposed through said bearing shoulder, a cutting element, a holder for said cutting element, pivotally mounted on said pivot shaft and held against movement longitudinally thereof, and a sleeve rotatably connected to said pivot shaft and engaging the external threads on said shoulder for moving said pivot shaft longitudinally to adjust said element in said head, and a locking 15 member engaging said external threads, combined with another cutting element relative to which the said shaft and its suspended cutting element is adjusted.

8. A shaper or planer tool comprising a head having outwardly extending alined externally screw-threaded tubular bearing shoulders, a pivot shaft mounted in the bearings formed by the said shoulders and having an eccentric within the head, a tool 20 holder mounted on and depending from the said eccentric and held thereon from movement longitudinally of the shaft, a collar screwed on one of the said shoulders and having means for engaging the said shaft to 25 adjust it longitudinally while permitting it to be turned, and a sleeve screwed on the other shoulder and having means for engaging the shaft to adjust it around its axis while leaving the shaft free to move longitudinally.

9. A shaper or planer tool comprising a head having an outwardly extending externally threaded bearing shoulder, a pivot shaft disposed through said shoulder and 45 provided with an eccentric, a cutting element, a holder for said cutting element pivotally mounted upon said eccentric, and means for engaging the threads on said shoulder to adjust said element vertically in 50 said head, combined with another cutting element relative to which the said shaft and its suspended cutting element is adjusted.

10. A shaper or planer tool comprising a head having an outwardly extending externally threaded bearing shoulder, a pivot shaft disposed through said shoulder and

provided with an eccentric, a cutting element, a holder for said cutting element pivotally mounted upon said eccentric, means for engaging the threads on said shoulder to adjust said element vertically in 60 said head, and a locking member engaging said external threads for maintaining said element in vertically adjusted position, combined with another cutting element relative 65 to which the said shaft and its suspended cutting element is adjusted.

11. A shaper or planer tool comprising a head having outwardly extending alined externally threaded bearing shoulders, a pivot 70 shaft disposed through said bearing shoulders and having an eccentric disposed within the head, a cutting element, a holder for said cutting element engaging said eccentric and fixed against independent movement 75 longitudinally of said pivot shaft, means engaging one end of said pivot shaft and the adjacent bearing shoulder for moving the pivot shaft longitudinally to adjust said element transversely in the head, and means 80 engaging the other end of said pivot shaft and the adjacent shoulder for rotating the pivot shaft to adjust said element vertically in said head, combined with another cutting element relative to which the said shaft and 85 its suspended cutting element is adjusted.

12. A shaper or planer tool comprising a head having outwardly extending alined externally screw-threaded tubular bearing shoulders, a pivot shaft mounted in the bearings formed by the said shoulders and having an eccentric within the head, a tool 90 holder mounted on and depending from the said eccentric and held thereon from movement longitudinally of the shaft, a collar 95 screwed on one of the said shoulders and having means for engaging the said shaft to adjust it longitudinally while permitting it to be turned, and a sleeve screwed on the other shoulder and having means for engaging the shaft to adjust it around its axis while leaving the shaft free to move longitudinally, combined with another tool holder mounted in the said head and relative to which the first tool holder is adjustable by 100 the movements of the said shaft.

Signed this 23rd day of May, 1914, in the presence of two witnesses.
